UNITED STATES PATENT OFFICE.

WALTER L. WILLIAMS, OF SOUTH RICHMOND, VIRGINIA.

IRONING-BOARD CABINET.

Application filed June 2, 1923. Serial No. 643,040.

The object of the present invention is to provide an ironing board cabinet which shall have two ironing boards one of which is adapted to serve as a door for the cabinet.

5 The combined door and ironing board is attached to the cabinet in such a manner that when the door is used as an ironing board, there are no supports or projecting members outside of the cabinet, thus leaving the ironing board clear on all sides and making it more useful and convenient than would be the case if struts or other like supports were used in supporting the board. The second ironing board is so mounted 10 with respect to the first that it may remain in the cabinet without interfering in any way with the use of the first. The novel features of the invention resides in the manner of mounting the two boards with respect 15 to each other, and in other features, as will more fully appear from the detailed description taken in connection with the accompanying drawing and the claims.

20 The various features of novelty and invention will appear from the detailed description taken in connection with the accompanying drawing forming part of this specification.

25 Referring to the drawings, Fig. 1 is a vertical section from front to back of the improved cabinet and showing the same as set into a wall some distance above the floor, the cabinet being closed;

30 Fig. 2 is a view similar to Fig. 1, but showing both ironing boards as opened out in position for use;

35 Fig. 3 is a perspective view of the improved cabinet showing the main ironing board in position for use, and

40 Fig. 4 is a perspective view of one of the brackets to which the inner end of the door or main ironing board is secured.

45 In the drawings, the improved cabinet is generally indicated at 12 and is shown as being set into a wall 11 a convenient distance above the floor line 10. In general outline, the cabinet is of rectangular form, and the bottom and back thereof can be made of any suitable material, such as sheet metal, while the sides 13 thereof are preferably made of wood.

50 The front of the cabinet has a wall 15 provided with a cut-out corresponding to the outline of the ironing board 14. For convenience of description, the wall 15 may

hereinafter also be referred to as a closure member for the cabinet and the ironing board 14 as a door. The ironing board 14 and wall 15 are preferably originally one 60 piece of board, the ironing board being sawed out from the board and the remainder of the board then utilized as a wall. This method of making the ironing board and wall very materially reduces the cost 65 of manufacture of the cabinet. The ironing board 14 is turnably mounted on an axis defined by a horizontally extending rod or shaft 16 which is turnably anchored at its ends in any suitable manner to the inside 70 face of the wall 15 some distance above the floor of the cabinet.

75 The ironing board is affixed to the shaft 16 by means of a pair of brackets, generally indicated at 17, one bracket being disposed on each side of the rear end of the ironing board and being turnably mounted on the shaft as will presently appear. The shaft 16 intermediate its ends is anchored to the ironing board 14 by means of a suitable anchoring device 14'. By anchoring the shaft 16 to the ironing board by means of the anchoring device 14' not only is the shaft held against axial movement but the ironing board is prevented from warping between 80 its longitudinal edges.

85 In Fig. 4, the bracket is shown as having a plate-like body portion 18 from the bottom of which projects a shelf 19 and a step 20 below the shelf and in front thereof. This bracket is adapted to be slipped over the side of the ironing board, the shelf 19 overlying the board and the step 20 serving to support the board, there being an 90 opening 21 in the end of the step through which securing means may be passed for holding the bracket in position on the board. The shelf 19 is also provided with openings 19' through which securing means 95 may be passed into the ironing board for additionally securing the bracket in place on the same. It will be understood that the brackets 17 are made in rights and lefts, but are otherwise the same.

100 The plate 18 is provided with an opening 22 above the step 20 so that the bracket can be received over the end of the shaft 16. The shaft will extend across the ironing board on the top thereof, and consequently when the ironing board is in upright position and the cabinet closed, it will 105 110

not be visible. At the rear of the cabinet is a transversely extending block 23, which serves as an abutment against which the inner end of the ironing board may abut when 5 the board is disposed in horizontal position or a position for use, as clearly indicated in Fig. 2. Each bracket 17 is also provided with a laterally bent flange or abutment member 28 adjacent its upper end. These 10 abutment members are adapted to engage the sides of the partial closure member 15 when the main ironing board is horizontally disposed as shown in Fig. 3, and are intended to supplement the block 23 at the 15 back of the cabinet. However, if desired, the block 23 can be dispensed with, the abutment 28 on the bracket 17 then serving to hold the ironing board in working position.

Associated with the ironing board 14 is 20 an auxilliary ironing board having long and short sections, the longer leg 24 of which constitutes the ironing board proper, the shorter leg 25 thereof being horizontally connected to the shaft 16 in any suitable 25 manner, as by strap eyes 26. The length of the leg 25 is such that the leg 24 may be turned at right angles to the door or ironing board 14 and be disposed within the 30 cabinet when the ironing board 14 is positioned for use, as will be fully understood by reference to Fig. 3.

When the leg or ironing board 24 is swung 35 out of the cabinet under the board 14, as shown in Fig. 2, it is maintained in position by means of the bracket lugs 27 which project laterally from the body plate 18 of the bracket 17 into the path of movement of the leg 25. By reason of this construction, it will be seen that the smaller ironing board 40 24 is solidly held when in working position and that the strain on the parts is reduced to a minimum.

The top of the bracket plate 18 is further bent as at 29 to reinforce the member 45 28 and also to provide an anchorage for one end of the spring 30, which is also anchored to the bottom of the cabinet near the front thereof. This spring is of sufficient 50 strength to prevent the door or ironing board 14 from opening out after it has been brought to upright position for closing the cabinet. When the door is disposed in horizontal position, the weight of the same is sufficient to maintain it in that position, and for the further reason that as it is swung 55 to a horizontal position, the spring 30 approaches the shaft 16, thus shortening the effective lever arm on which the spring acts.

By mounting the door or ironing board 60 in the manner indicated, plenty room is provided within the cabinet for the provision of shelves 31 and the like, for supporting various objects such as sad irons or other household implements.

65 From the above construction, it will be

seen that I have provided an ironing cabinet which can be simply manufactured and which consists of very few parts. By hinging the ironing board in the manner indicated not only is a very stable ironing support obtained, but a closure for the front of the cabinet is also obtained. The idea of utilizing the ironing board as a door or closure for the cabinet is an important feature 70 of the invention. While I have described the invention with considerable particularity of detail, it is to be understood that no unnecessary limitations are intended on the 75 claimed invention.

What I claim is:

1. In an ironing board cabinet, a shaft extending horizontally across the cabinet above bottom and adjacent the front of the cabinet, an ironing board of less width than the width of the cabinet, a pair of upright brackets one at each side of the ironing board adjacent the rear end thereof, said brackets being mounted on the shaft and supporting the ironing board, the said brackets being spaced from the side walls 85 of the cabinet, and spring means disposed between the brackets and the walls of the cabinet for maintaining the ironing board 90 in upright position.

2. The combination with a support of a 95 cabinet, of a pair of brackets fixed to the support and disposed in transverse horizontal alignment, laterally directed stops at the forward edges of the brackets, an ironing board having long and short leg sections 100 pivotally mounted on the support, the stops extending into the path of movement of the shorter leg of the ironing board and serving to maintain the longer leg in a horizontal 105 position.

3. The combination with a support capable of being arranged in either a vertical or horizontal position, a horizontally disposed shaft secured to the support, means to support the ends of the shaft, a pair of 110 brackets received over the ends of the shaft, an ironing board having long and short leg sections disposed between the brackets and having its shorter leg hingedly connected with the shaft, means on the brackets for limiting the turning movement of the ironing board toward the support, and means also carried by the brackets for limiting the pivotal movement of the support in one 115 direction.

4. The combination with a pair of parallel vertically disposed supports and a normally horizontally disposed support, of a pair of brackets secured to the vertically 125 disposed supports and arranged in horizontal transverse alignment, means for pivotally supporting the normally horizontally disposed support on the brackets, spaced laterally extending attaching elements formed 130 on the lower end on each of the brackets 135

and adapted to straddle one end of the normally horizontally disposed support, fastenings for securing the laterally extending elements to the normally horizontally disposed support, an inwardly directed vertically extended flange formed on the forward edge of each of the brackets, an ironing board having long and short leg sections, its shorter leg pivoted to the normally horizontally disposed support and capable of being arranged to extend parallel to such

support or at right angles thereto, the shorter leg of the ironing board being adapted to abut the flanges when the ironing board is in a position parallel to the support, and the support being capable of being arranged in a vertical position where it rests against the flanges. ¹⁵

In testimony whereof I affix my signature.

WALTER L. WILLIAMS.
